UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

REFRIGERATOR.

Application filed August 18, 1924. Serial No. 732,677.

This invention relates to a refrigerator, more particularly pertaining to a novel construction of the refrigerator shells, and has for its object the construction of such shells 5 so that the total weight of the refrigerator is reduced to a minimum.

One of the difficulties in a cast stone refrigerator has been that it is considerably heavier than the ordinary wood refrigerator 10 most commonly used. The stone refrigerator construction, however, has many advantages over the wood construction and they are coming into favor in spite of the fact that their weight is considerable.

15 Another advantage in this construction is that the built-up fibrous or wooden shell structure may be used as one of the moulds in moulding the stone work around the fibrous shell. In a stone refrigerator, where 20 the shell is formed of a solid moulded artificial stone, it is necessary to use an outer mould and an inner mould, whereas in this construction the frame shell structure, which serves as one of the mould parts, may be 25 constructed at a greatly reduced cost than the mould part used in moulding a solid stone refrigerator.

In the drawings:

Fig. 1 is a vertical sectional view through 30 a refrigerator constructed in accordance with my invention.

Fig. 2 is a horizontal section taken substantially on the line 2—2 of Fig. 1.

Fig. 3 is a vertical section taken on the 35 line 3—3 of Fig. 1.

Fig. 4 is a perspective view with parts broken away, showing my composite outer shell.

Fig. 5 is a perspective view with parts 40 broken away, showing my composite inner shell.

Fig. 6 is a perspective view of the wood frame forming the inner shell before the stonework is moulded thereto.

Fig. 7 is a perspective view of the wood frame forming the outer shell before the stonework is moulded thereon.

Fig. 8 is a detail of the roughened or splintered wood, showing how the moulded 50 stone is secured thereto.

The outer shell is first built up by securing together the wooden frame members *a*, by gluing or otherwise securing together.

A plurality of large-headed nails *c* are partially embedded in the outside surface of this

frame structure. There are a great number of these fastening devices used, and obviously other forms of fastening devices could be used instead of these nails. Instead of these fastening devices, the outer surface of the wooden frame may be roughened or splintered by a suitable tool, (Fig. 8). The cement or stonework when hardened will be securely tied to the wood frame because of the fact that the cement flows around the raised splinters of the wood frame. This outer frame structure, preferably of gum wood or poplar, is then located within an outer mould so that the outside surface of the frame structure will be spaced from the inside surface of the outer mould at a distance of approximately three-eighths of an inch. Obviously this spacing could be varied when the requirements of the refrigerator are such that it is necessary to form a thicker stone covering for the outer refrigerator shell. The stonework *d*, which is preferably an oxy-chloride cement, is now poured into the mould and formed about the fibrous outer shell, and forms a covering for the outer 80 surface thereof. When this cement hardens, it is securely keyed to the frames by means of the fastening devices.

Similarly, the inner shell is first built up of a frame structure *e* of fibrous material, 85 preferably of the same quality and grade as is the frame structure forming the outer shell. These wooden frame members may be glued or otherwise secured together. To finish this inner shell it is desired to cover 90 the inside surface of the shell with a covering of moulded artificial stone, and I preferably use oxy-chloride cement therefor. This covering of oxy-chloride cement is cast-united to the inside surface of the inner shell 95 in the same way as is the covering for the outer shell. The fastening devices *g*, which are here shown as large-headed nails, partly driven into the frame structure, securely key the stonework to the frame by embedding 100 the heads of the nails in the stonework. The splintering process keys the stone work to the frame work in a like manner by embedding the splintered or roughened surface of the wood in the stone.

The inner shell may be secured to the outer shell by clamping the same in a manner that is disclosed in my prior application, Serial No. 715,045. To clamp the inner shell to the outer shell, I secure the angle strips *h* 110

to the back of the front wall of the outer shell, and locate these angle strips in such a way that the inner shell may be fitted therein and is partially supported thereby. The 5 clamping straps *i* are anchored to these angles in a manner shown in my prior application, these straps being drawn taut about the inner shell and clamped together as at *j*. This secures the inner shell to the 10 outer shell, and securely clamps the inner shell up against the front of the outer shell, the angles being so positioned as to locate the inner shell with respect to the outer shell. The inner shell also may be cast-united to 15 the outer shell in a manner as disclosed in my prior application, Serial No. 721,823.

Layers of cork board *k* are nailed or otherwise secured to the inside surface of the outer shell, as shown at *m*. This forms a 20 complete lining of cork board for the outer shell, and may be secured to the outer shell before the inner shell is clamped in place. After the inner shell has been secured and clamped to the outer shell, the space between 25 the inner shell and the outer shell may be filled with an insulating material, which is preferably formed of cork fragments and a binder, such as mineral pitch, shown in my prior application, Serial No. 716,612. This 30 insulating material, when hardened, will fill all the interstices existing between the inner and outer shells and form a solid unit of the refrigerator. The back of the inner shell may have secured thereto a fibrous strip *n*, 35 running up and down, and the layers of cork board *o* may be fitted behind the inner shell and the back plate *e*, secured in the opening of the back of the refrigerator for closing the same. This back plate is secured to the 40 outer shell as at *q*, and to the strip *n* carried by the inner shell, as at *r*. In this way, the inner shell is securely supported at the back.

What I claim is:

1. In a refrigerator or cabinet construction, the combination of interfitting sections 45 secured together in spaced relation, each comprising a fibrous shell structure, and a covering of plastically applied stone secured thereto.
2. In a refrigerator or cabinet construction, the combination of inner and outer sections secured together, one of said sections comprising a shell-like frame of fibrous material, and having a covering of plastically applied stone work secured thereto.
3. In a refrigerator or cabinet construction, the combination of inner and outer sections secured together in spaced relation, one of said sections comprising a shell-like 60 frame of wood, and a covering of cast stone cast-united thereto.
4. In a refrigerator or cabinet construction, the combination of inner and outer sections secured together, one of said sections 65 comprising a frame structure of fibrous ma-

terial, a covering of moulded stone work for said frame structure, and fastening devices for securing the moulded stone work to said fibrous frame.

5. In a refrigerator or cabinet construction, 70 the combination of interfitting sections, the outer section comprising a shell-like frame structure of fibrous material and a covering of moulded stone work cast-united to the outside thereof, the inner section comprising a shell-like frame structure of fibrous material and a covering of moulded stone work cast-united 75 to the inside surface of said fibrous frame, and means for securing the inner and outer shells together.

6. In a refrigerator or cabinet construction, the combination of interfitting sections 80 secured together, each section comprising a shell and mould of fibrous material, and a moulded stone work covering cast-united to 85 said fibrous shell and mould.

7. In a refrigerator or cabinet construction, the combination of interfitting sections 90 secured together, each section comprising a relatively thick fibrous shell, and a layer of plastically applied stone work entirely covering said shells and secured thereto.

8. In a refrigerator or cabinet construction, the combination of an inner and outer 95 shell of moulded stone secured together, and each provided with an intervening box structure of fibrous material cast-united therewith.

9. In a refrigerator or cabinet construction, 100 the combination of an inner and outer shell of moulded stone secured together, one of said shells provided with an intervening wooden reinforcing box structure embedded therein.

10. In a refrigerator or cabinet construction, 105 the combination of an inner and outer shell of moulded stone secured together in spaced relation and each provided with an intervening reinforcing wood box structure secured thereto, and a binder material arranged to fill the space between said shells.

11. In a refrigerator, or cabinet construction, the combination of two cores fitted together, one of said cores comprising a shell-like framework of fibrous material, and both of said cores having a coating of stonework applied in a fluid state and allowed to set in a monolithic coating.

12. In a refrigerator, or cabinet construction, the combination of a wooden core, or reinforcing structure, giving shape to the cabinet, or refrigerator, and defining the chamber, or chambers thereof, and a shell of cast stone cast-united to the interior walls 110 of said core.

13. A refrigerator, or cabinet construction, 115 comprising a shell structure of wood boards fitted to give shape to the cabinet, or refrigerator, and a coating of stonework applied in a fluid state to the surfaces of 120

said shell and allowed to set in a solid monolithic coating.

14. A refrigerator or cabinet, in which is located a wooden core structure to give the same shape and reinforce the same and define the chamber or chambers, and in which the exposed surface of the wooden core structure is coated with a plastically applied hardened cement adhering directly to such wooden core structure.

15. A refrigerator or cabinet, comprising a wooden core or reinforcing structure giving shape to the cabinet or the refrigerator and defining the chamber or chambers, and a stonelike exterior and interior surface for

the cabinet of the refrigerator applied in the fluid state and allowed to set, whereby such stone coatings are carried and reinforced by the wooden core structure.

16. A refrigerator, or cabinet construction, comprising a shell structure of fibrous material, fitted to give shape to the cabinet, or refrigerator, and a coating of stone-work applied in a fluid state to the surfaces of said shell and allowed to set in a solid monolithic coating.

In testimony whereof I have affixed my signature.

LLOYD G. COPEMAN.
